FIG. 1 is a top view of an embodiment of a heat sealed pipette tube end showing my new design;

FIG. 2 is a bottom view of the heat sealed pipette tube end shown in FIG. 1;

FIG. 3 is a left side elevational view of the heat sealed pipette tube end shown in FIG. 1;

FIG. 4 is a right side elevational view of the heat sealed pipette tube end shown in FIG. 1;

FIG. 5 is a front elevational view of the heat sealed pipette tube end shown in FIG. 1; and,

FIG. 6 is a rear elevation view of the heat sealed pipette tube end shown in FIG. 1.

The broken lines immediately adjacent the claimed areas represent the bounds of the claim, and all other broken lines are included for the purpose of illustrating portions of the heat sealed pipette tube end that form no part of the claimed design. None of the broken lines form a part of the claimed design.
